UNITED STATES PATENT OFFICE.

FRANK D. SPOTSWOOD, OF LEXINGTON, KENTUCKY.

INDICATOR-CARD.

1,333,686.

Specification of Letters Patent. Patented Mar. 16, 1920.

Application filed January 25, 1918. Serial No. 213,717.

To all whom it may concern:

Be it known that I, FRANK D. SPOTSWOOD, a citizen of the United States, residing at Lexington, in the county of Fayette and 5 State of Kentucky, have invented certain new and useful Improvements in Indicator-Cards, of which the following is a specification.

This invention relates to indicator cards 10 and has as its object to provide an indicator card which may be produced at a very low cost, which will be employed to register small amounts of money paid out during the day or week so that the user at the end 15 of any selected period may be apprised of the amount which he has spent during the day.

The card embodying the present invention, in the preferred embodiment thereof, 20 consists of two facing sheets which constitute the front and back of the device, and indicator disks which are rotatably mounted between these sheets and which bear indicia designed, in the rotation of the disks, to be 25 brought opposite eight openings formed in one of the said sheets, and it is one aim of the invention to utilize the pivots for the disks as the sole means for securing together the said sheets and the disks in assembled 30 relation, so that the employment of filler or spacing members, corner fastenings, and the like, is entirely obviated.

In the accompanying drawings:

Figure 1 is a perspective view of one embodiment of the invention, the card shown in the said figure being designed for use in the registration of amounts of money spent during a day or other selected period;

Fig. 2 is a horizontal sectional view on the 40 line 2—2 of Fig. 1;

Fig. 3 is a vertical sectional view on the line 3—3 of Fig. 1;

Fig. 4 is a plan view of one of the rotary disks of the card;

Fig. 5 is a similar view of the other disk;

Fig. 6 is a rear elevation of the card shown in Fig. 1.

So far as structure is concerned, the device comprises a facing sheet 1, a backing 50 sheet 2, and rotary disks which will be hereafter more specifically described. The facing and backing sheets are preferably substantially rectangular in form, as clearly shown in Figs. 1 and 6 of the drawings, and 55 are of cardboard, celluloid, or any other material suitable for the purpose and are suffi-

ciently rigid to provide against bending or crumpling when placed in one's pocket. The facing and backing sheets 1 and 2 are formed in each end each with a finger notch and these notches are indicated respectively, by the numerals 3 and 4 and the notches in the two sheets are located directly opposite each other in the assembled relation of the sheets and are preferably relatively deep as shown 65 in the drawings. While the exact shape of these notches is immaterial, I prefer to make them substantially semi-circular, each cut on an arc of a circle whose center is at the end edge of the sheet. The result is that the 70 end walls of the notch form substantially right angles with the line of the end of the sheet, as shown. The facing sheet 1 in Fig. 1 is formed near its upper edge and at opposite sides of its midlength with eight 75 openings one indicated by the numeral 5 and the other by the numeral 6, which openings serve a purpose to be presently explained, and it is preferable that the face of the sheet 1 have printed thereon adjacent to the opening 5, the word "Dollars" as indicated by the numeral 7, and adjacent to the opening 6 the word "Cents", as indicated by the numeral 8. Any suitable advertising matter may also be printed upon this face 80 of the sheet, and, of course, the backing sheet 2 may have printed upon its face any desired advertising matter.

In that form of the invention shown, the disks which are arranged between the facing and backing sheets, are indicated one by the numeral 14 and the other by the numeral 15. These disks are disposed edge to edge and slightly spaced from each other and in a single plane between the said sheets 90 1 and 2, and eyelet rivets or any other suitable fastening elements 16 are passed loosely through the centers of the disks and engaged with the said sheets 1 and 2, thus securing the sheets and disks together in their assembled relation and at the same time providing pivots about which the disks may be 95 rotated, the rivets 16 being clamped with sufficient firmness to cause the opposing faces of the sheets 1 and 2 to exert a slight friction against the opposite faces of the disks 14 and 15 so as to hold the disks against accidental rotation and yet permit of the disks being rotated manually when the finger is engaged with the peripheries thereof 100 in the finger notches 3 and 4. By reference now to the drawings it will be noted that 105 110

the superposed sheets are wider than the diameter of the disks and somewhat longer than twice such diameter. As a result no part of either disk projects beyond any edge of the sheets. Also it may be observed that while the peripheral portions of the disks 14 and 15 extend into the finger notches 3 and 4, nevertheless the peripheries of the disks are spaced inwardly a considerable distance from the end edges of the facing sheets 1 and 2 so that when the card is carried in one's pocket there is no likelihood of the peripheries of the disks being engaged either by the walls of the pocket or by the other articles within the pocket which will be likely to accidentally rotate the disks and thus disturb their adjusted positions. The disk 14 has printed upon its obverse face next adjacent the facing sheet 1, an annular series of circles 16 within which are printed numerals running consecutively in the series in numerical order from 1 to 19, the circular space between the numeral spaces 1 and 19 being left blank so as to constitute a zero space. The disk 15 has printed upon its corresponding obverse face an annular series of circles 17 in which are printed numbers arranged, of course, in an annular series and beginning with the number 5 and terminating with the number 95, each succeeding number in the series being greater by five than the number preceding it. There is also a blank circle 18 left between the numbers 5 and 95 to constitute a zero space as in the case of the disk 14. Referring now to Fig. 1 of the drawings it will be observed that the disks 14 and 15 are so arranged between the sheets 1 and 2 of the card that in the rotation of the disks, the numbers upon the disk 14 will be brought successively into position opposite the sight opening 5 and the numbers upon the disk 15 will be brought successively opposite the sight opening 6. Consequently, the numbers upon the disk 14 indicate dollars and

the numbers upon the disk 15 indicate cents. At the beginning of the day or other selected period the disks will, of course, be so rotated that the blank circles upon the two disks will be opposite the sight openings 5 and 6 and then as amounts of money are spent during the selected period the disks will be rotated to indicate the totals spent so that at the end of the period the user of the card may be apprised of the exact amount which he has spent during the period. The object of this card is to induce economy and it, therefore, possesses value in this respect as well as an advertising medium.

The rear facing sheet will have printed thereon the names of six or more consecutive months and the Saturday dates in each of said months, so that the user of the card may write in the spaces provided opposite the said Saturday dates the total amount spent during the week ending on such date and then at the end of the six months may total the amount spent during said period, this arrangement being shown in Fig. 6 of the drawings.

Having thus described the invention, what is claimed as new is:

An article of the class described comprising two disks disposed edge to edge, a ring of figures on one disk designating dollars and a ring of figures on the other disk designating cents, facing sheets between which said disks are pivoted, the front sheet having sight openings to respectively expose a single figure in each ring and both sheets having edge notches exposing the peripheries of the disks for permitting them to be turned manually, legends on the reverse of the back sheet indicating periods of time, and opposite each legend a space for entering the total amount registered by the disks within any such period.

In testimony whereof I affix my signature.
FRANK D. SPOTSWOOD. [L.S.]
